INVENTOR:
F. E. Wadham,

By Wm. F. Hendrikse,

UNITED STATES PATENT OFFICE

FREDERICK E. WADHAMS, OF CHICAGO, ILLINOIS, ASSIGNOR TO LINCOLN-SCHLUETER FLOOR MACHINERY CO., A CORPORATION OF ILLINOIS

FLOOR-TREATING MACHINE

Application filed November 13, 1926. Serial No. 148,152.

The present invention has for its object to produce a compact floor treating machine made of a few simple parts, rugged in construction, and efficient in operation.

5 The invention relates particularly to small machines supported from the surface to be treated by the treating elements and carrying a motor for rotating the treating elements; the machines being adapted to be pushed by 10 hand over the floor or other surface which is being treated. Machines of this kind are used for scrubbing, polishing, sanding, sweeping or waxing floors by means of brushes or other elements having comparatively large bearing 15 areas for engagement with the floors. There is always more or less unevenness in the surface of a floor and therefore, if the treating elements are compelled to rotate about fixed vertical axes, they will not adapt themselves to the irregularities of the floor, and care must be taken to shift the machines in 20 various directions from a straight line travel, in order to permit the treating elements to operate on all points of the surface of the floor. Furthermore, the treating elements vary with the nature of the work and must therefore be changed in order to provide the proper elements to suit the character of the work being done, and they must also be 25 changed when they have become worn out. Viewed in one of its aspects, the present invention may be said to have for its object to produce a simple and novel means for attaching the rotary treating elements of a floor 30 treating machine in such a way that they may readily be attached and detached and, while in operation, may shift their axes of rotation angularly to compensate for unevenness in the floor that is being treated; whereby the movement of a machine ahead in a straight line 35 will finish all points of the surface lying within the area traversed by the machine.

The various features of novelty whereby my invention is characterized will herein 40 after be pointed out with particularity in the claims; but, for a full understanding of my invention and of its objects and advantages, reference may be had to the following detailed description taken in connection with 45 the accompanying drawings, wherein:

Figure 1 is a side elevation of a machine arranged in accordance with the present invention, the greater portion of the handle being broken away; Fig. 2 is a front view of the machine; Fig. 3 is a top plan view of the machine, on a larger scale than Figs. 1 and 2, with the top, including the motor, removed; Fig. 4 is a section taken approximately on line 4-4 of Fig. 3, on a larger scale than Fig. 3; Fig. 5 is a top plan view of the hub or socket of one of the floor treating members, detached from the latter; Fig. 6 is a section taken approximately on line 6-6 of Fig. 5; and Fig. 7 is a vertical central section, on an enlarged scale through the double bearing 55 for one of the vertical shafts by means of which the treating elements are rotated.

Referring to the drawings, 1 represents an elongated casing in the form of a shallow flat bottom pan, the casing being preferably made of a single piece of heavy sheet metal pressed into shape. The casing is closed at the top by means of a cover 2 that is preferably made of a flat piece of sheet metal having along the edges a flange 3 that will fit around the upper marginal portions of the side walls of the casing. The cover may be fastened in place by a few small screws 4. One of the long edges of the casing is the front. Mounted on the cover, symmetrically disposed with respect to the sides or ends, and toward the rear of the cover, is a suitable motor 5 to which may be attached an operating handle 6 by means of which the machine may be pushed about. Suitable truck wheels 7 may be supported from brackets 8 extending rearwardly 60 from the underside of the casing.

Within the casing are arranged two large spiral gears 9 and 10 meshing with each other. The motor shaft 11 extends down into the casing and has thereon a spiral pinion 12 made of metal and meshing with the pinion 9. With this arrangement, the motor may rotate at a high speed, while the gear wheels 9 and 10 revolve at the speed desired 65 for the floor treating elements, without the use of any intermediate speed changing mechanism. The gears 9 and 10 are fixed to the upper ends of vertical shafts 13 and 14 that extend downwardly through the bottom 70

of the casing. The shafts 13 and 14, with their bearings, are preferably made in complete detachable units that may be firmly anchored to the comparatively light bottom of the casing. The bearings for each of the shafts 13 and 14 are in housings 15, there being one of these housings associated with each of the shafts. As best shown in Fig. 4, the bottom of the casing has two large holes, each 10 of a size to receive one of the bearing housings. Each housing is fitted into two cup-shaped holding members 16 and 17, one lying above and the other below the bottom of the casing. Each holding member has around 15 the mouth a flange or rim 18 that rests flat against the bottom of the casing. Bolts 19 pass through the overlying flanges of the holding members and through the casing bottom that lies between the flanges; the holding 20 members being thus firmly fastened to the casing and firmly clamped about the bearing housings.

The construction of the double bearings for the shafts 14 and 15 is best shown in Fig. 7. 25 The bearing housing is in the form of a wide ring having two internal ball races 20 and 21 extending around the same. On the shaft 14, or 15 as the case may be, is fixed a collar 22 containing external ball races 24 and 25 30 facing respectively the races 20 and 21. Arranged between the cooperating races 20 and 24 are balls 26, while another set of balls 27 runs in the races 21 and 25. Suitable spacing rings 28 are provided to hold the balls in each 35 group or set at the proper distances apart. The double bearings for each of the shafts 14 and 15 serve not only as anti-friction bearings that permit the shafts to rotate freely while held against angular movement of any 40 kind, but they also serve as thrust bearings to take end thrusts on the shafts, in either direction. The pressure transmitted through the ball bearings is distributed by the flanged holding members 16 and 17 over a considerable 45 area of the bottom of the casing, so that the casing may be made of comparatively light material without danger of distortion under load. The upper sides of the bearings are exposed within the casing which may be 50 dust proof; but the underside of each of the bearings is exposed to dirt and water from the surface which is being treated. In order to protect the bearings against the entrances of foreign matter from underneath, I place 55 around the shafts 14 and 15, underneath the bearings, a packing 29 of felt or the like, this packing being conveniently held in place by a small sheet metal gland 30 extending through an opening in the bottom of the cup-shaped holding member 17.

Each of the shafts 14 and 15 has an enlarged lower end 32 lying below the bearing. Near the lower end of each of the parts 32 is a cross pin 33 that projects at both ends. 65 Above the pin 33 is a loose washer 34, and

between the washer 34 and a collar 35 on the shaft, is a coiled spring 36 surrounding the shaft.

Each of the treating elements 37 is provided at the center with a hub 38 having a 70 central opening 39 extending through the same. The bottom of the opening 39 has substantially the same diameter as the diameter of the lower end of one of the shaft sections 75 32, increasing gradually in diameter toward the top. A slot 40 is cut through the upper portion of the hub across the diameter of the opening 39, this slot having a width slightly greater than the diameter of the pin 33. The hub is undercut at each side of the slot, to 80 form four seats, as indicated at 41, the vertical height of the seats being somewhat greater than the diameter of the pin 33.

In applying a treating element to the supporting shaft therefor, the lower end of the shaft is inserted in the opening 39, with the pin 85 registering with the slot 40. The shaft is then pushed down until the pin reaches the undercut 41, and is given a quarter turn to lock the treating element and shaft together. 90 As the shaft is pushed down into the socket, the washer 34 is arrested by the top of the socket, so as to compress the spring. Therefore, when there is no weight on the treating element, the spring forces the latter down 95 until the pin is frictionally held against the overhanging portions of the hub. When the treating elements are in place and the machine is set on a floor, the weight of the machine compresses the springs somewhat, as 100 shown in Fig. 4, so that the pins 33 do not touch either the overhanging or underlying portions of the hub or socket. When the motor is set in operation, the treating elements are compelled to revolve with the shafts, but 105 cannot accidentally become detached therefrom. By making the openings 39 in the hubs or sockets tapering, the treating elements are permitted to wobble on the driving shafts so as to accommodate themselves to 110 undulations in the floor.

It will thus be seen that my improved machine is very simple but rugged in construction, that it will operate with a minimum of noise and will operate as effectively on uneven floors as on even floors; the body being made of two simple stampings; there being only three gear elements, one on the driving shaft and the others on the two driven shafts, and there being no metal to metal contact between the gear elements; the driven shafts having bearings securely supported from the bottom of the body member and permitting free rotation of the shafts under end thrusts and holding the shafts against endwise movements; and the treating elements being easily attached and detached and, in use, being capable of adjusting themselves to unevenness in the surface that is being treated.

It will also be seen that by providing the 130

hub with undercuts or seats on both sides of each end of the slot 40, the treating elements may be locked to their shafts by turning them either to the right or to the left after the pins 5 have been pushed down into the slots. This is of advantage in that the two floor treating elements may be interchanged after wear takes place, with the pins always lying in the seats ahead of the same in the direction of rotation 10 of the treating elements. In the case of brushes, the bristles in time will tend to assume a horizontal position so that the sides of the bristles, instead of the ends engage the floor. Therefore, before the bristles have taken 15 a permanent set out of the vertical positions, the brushes may be interchanged so as to produce a tendency to swing the bristles in the opposite direction from the vertical. In the case of a sanding element, rotation in one direction dulls the edges on one side of 20 the grains of sand; and, by interchanging the two elements, the opposite, sharp sides of the grains are brought into play.

While I have illustrated and described with 25 particularity only a single preferred form of my invention, I do not desire to be limited to the exact structural details thus illustrated and described; but intend to cover all forms and arrangements which come within the 30 definitions of my invention constituting the appended claims.

I claim:

1. In a floor treating machine, a body member having a vertical rotatable shaft projecting 35 downwardly therefrom, a floor-treating element having a central tapered opening smallest in diameter at the lower end and a slot extending into the same diametrically of said opening and undercut at opposite sides 40 of the opening, a cross pin on the lower end of the shaft having a diameter small enough to permit it to pass into the slot and not as great as the vertical height of the undercut portions of the slot, a shoulder on the shaft above the 45 floor treating element, and a compression spring between said shoulder and the top of said floor treating element.

2. In a floor treating machine, a body member having a vertical rotatable shaft projecting 50 downwardly therefrom, a floor-treating element having a central vertical bore and a slot extending diametrically of the bore, there being undercuts or seats at opposite sides of each end of the slot beside said bore, a cross 55 pin on the lower end of the shaft having a diameter small enough to permit it to pass into the slot and not as great as the vertical height of the undercuts or seats, a shoulder on the shaft above said element, and a compression spring between said shoulder and the top of said element.

In testimony whereof, I sign this specification.

FREDERICK E. WADHAMS.
